(57) **CLAIM**

The ornamental design for a digital still camera, as shown and described.

DESCRIPTION

FIG. 1 is a top and front perspective view of a digital still camera showing my new design;
FIG. 2 is a bottom and front perspective view thereof;
FIG. 3 is a top and rear perspective view thereof;
FIG. 4 is a front elevational view thereof;
FIG. 5 is a top plan view thereof;
FIG. 6 is a bottom plan view thereof;
FIG. 7 is a right side elevational view thereof;
FIG. 8 is a left side elevational view thereof; and,
FIG. 9 is a rear elevational view thereof

The broken lines depict portions of the digital still camera that form no part of the claimed design. Additionally, the dash-dot lines denote the boundary of the claim and form no part of the claimed design.
